ELECTRIC SWITCH

John J. Lawser, Philadelphia, Pa., assignor to
 Proctor Electric Company, Philadelphia, Pa.,
 a corporation of Pennsylvania

Application October 31, 1951, Serial No. 254,037

11 Claims. (Cl. 200—144)

1

The present invention relates to electrical switches of the type used in switching a load, such as a heating unit, from one electric supply line voltage to another.

The present invention is particularly applicable to wattage controllers of the type known as flashers, such as discussed in prior patents, for example U. S. Patent No. 2,357,225 issued August 29, 1944 to S. J. Roesch et al., and in the copending applications of W. H. Vogelsberg, Serial No. 157,933, filed April 25, 1950, and Serial No. 250,326, filed October 8, 1951. In these devices heating unit coils are initially overenergized and after a predetermined interval are reduced in energization. This causes rapid initial heating of the heating unit to some selected temperature and subsequent energization at a lower wattage to maintain the selected temperature. In one particular flasher switch, the connections for overenergization are maintained through a latch member. On release of the latch the blades move to a new position permitting a change in electric connections to thereby establish the lower wattage to the heating unit. Under certain circumstances it has been found that the movement of switch members from the overenergization position to the normal energization position may cause an arc-over phenomenon which has been termed "pop-over." This is due to the establishment of a sustained electrical arc between the first stationary contact position which is established at one potential and a second stationary contact position which is established at a different potential or is caused to operate at a different potential by the moving switch members. This situation is aggravated by high or overload currents that may be carried by the contacts, by bouncing of the contacts, by the absence of means to remove the arc products, etc.

It is a prime object of this invention to eliminate "pop-over" from wattage controllers.

It has been found that adding mass to the blades to obviate this "pop-over" condition causes only a small percentage of improvement. Under severe over-current conditions, increasing the mass of the moving blades does not give a sufficiently satisfactory solution. Moreover, increasing the mass presents problems of space limitations and aggravates the contact bounce problem.

Another object of this invention is to provide means in a wattage controller for obviating the "pop-over" problem without materially increasing the mass of the moving blade.

2

The present invention is illustrated in the accompanying drawings as applied to a device of the general type disclosed in the copending applications of W. H. Vogelsberg. The pertinent portion of the switch structure and simplified schematic diagrams of the circuit necessary for an understanding of the present invention are shown in the drawings and set forth in the description that follows.

- 10 In the drawings,
 Fig. 1 is an isometric view of the wattage controller to which the present invention is adapted;
 Fig. 2 is a simplified schematic circuit diagram of the controller in its overenergization position;
 15 Fig. 3 is similar to Fig. 2 with the parts in the normal energization position;
 Fig. 4 is a section through the controller of Fig. 1 taken along line 4—4;
 Fig. 5 is a partial front elevational view of the
 20 switch with the cover removed;
 Fig. 6 is a partial rear elevational view of the switch;
 Figs. 7 and 8 are sectional views taken along lines 7—7 and 8—8 of Fig. 5;
 25 Fig. 9 is an exploded isometric view of the elements of a latch construction of the present invention;
 Fig. 10 is a sectional view taken along line 10—10 of Fig. 4;
 30 Fig. 11 is a sectional view of a modified form of the latch construction, the view being taken along a plane indicated at 11—11 in Fig. 4;
 Fig. 12 is a fragmentary sectional view of the same taken similarly to Fig. 10;
 35 Fig. 13 is a perspective of one of the walls associated with the latch member;
 Fig. 14 is a perspective view of the latch member; and
 Fig. 15 is an explanatory graph.
 40 The wattage controller designated as 10 in Fig. 1 is of the type described in the aforementioned Vogelsberg applications. It comprises a switch case 11 and cover plate 12 by which it may be secured to the panel of an electric range.
 45 A manual control knob 13 is used to select the particular desired operating temperature of the heating unit to be controlled. Resistance coils R₁ and R₂ in Figs. 2 and 3 represent such a heating unit. In these figures some of the non-pertinent details are omitted for circuit simplification, but it will be understood that resistances R₁ and R₂ are subjected to overenergization during an initial heating period by the controller 10 from a supply line 15, and after rapid attainment of a predetermined tempera-

ture level by the heating coils or resistances, the circuit controller rearranges said resistances so that they receive normal energization. In the overenergization position as shown in Fig. 2, the controller serves to connect R_1 between L_1 and N of supply line 15, and to connect R_2 between L_2 and L_1 of the supply line. During the normal operation, as shown in Fig. 3, R_1 and R_2 are serially connected between L_1 and L_2 . If the voltage between N and either L_1 or L_2 is assumed to be 118 volts and the voltage between L_1 and L_2 is assumed to be 236 volts, and if it is assumed that R_2 is twice the resistance of R_1 , then the wattage during overenergization is approximately 4725 watts while during normal operation it is 2100 watts. The currents corresponding to these wattages amount to 18.4 amperes in either resistance coil during flash or overenergization, and 8.9 amps. in either coil during normal operation.

In the overenergization position (Fig. 2), the controller 10 acts through a movable switch blade 16 and a cooperating stationary contact 17 to supply a voltage at L_1 potential to the common connection of resistances R_1 and R_2 . The opposite end of resistance R_1 is connected to the neutral line N through a second movable switch blade 18 and a cooperating stationary contact 19, while the opposite end of resistance R_2 is connected through an adjustable thermostatic control switch 20 to line L_2 . In this overenergization position, switch blades 16 and 18 are held in engagement with contacts 17 and 19 by a bimetallic prop member 21 through a latch member 22. The bimetallic prop 21 is in shunt circuit with contacts 23 and 24 of the thermostatic switch 20, and at this time the prop 21 is not energized because contacts 23 and 24 are closed and serve to short-circuit the prop. A switch 25 is included in the shunt circuit with prop 21 to effect removal of the prop from the circuit during a normal energization period. This switch can be operated by the latch 22, or can be governed by a thermal relay. The alternate procedures are disclosed in the aforementioned applications.

At the end of the time interval as controlled by the thermostatic switch 20, contacts 23 and 24 open and cause energization of the bimetal prop 21. The latter, in response to the heating effect of current flow therethrough, flexes to release latch 22, thus permitting movement of switch blades 16 and 18 by their own self-bias into engagement with stationary contacts 26 and 27, respectively. These stationary contacts are serially connected and the circuit now established is such that current flows from L_1 through blade 16, through contact 26 to contact 27, through blade 18 to resistance R_1 , through resistance R_2 to the thermostatic switch 20 and then to line L_2 . Switch 25 is open at this time, thereby removing prop 21 from the circuit and preventing interference with operation of thermostatic switch 20.

It is during the switchover from the overenergization position shown in Fig. 2 to the normal energization shown in Fig. 3 that the "pop-over" phenomenon occurs. It will be appreciated that when blade 16 engages stationary contact 26, stationary contact 27 is established at L_1 potential. Thus movable blade 18, moving from stationary contact 19, which is established at N potential, to stationary contact 27 which becomes established at L_1 potential, will provide a situation wherein a movable member may draw an arc from a line conductor at one potential to a line conductor at a different potential. As previously mentioned,

there is a tendency for an arc, drawn upon disengagement of blade 18 and contact 19 to be drawn over to the stationary contact 27 which may be at L_1 potential before the arc becomes extinguished. By the present invention, the movement of blades 18 and 16, and particularly blade 18, is slowed down to a speed wherein any arc which may have been established between the moving blade 18 and the stationary contact 19 will be fully extinguished by the time blade 18 reaches the stationary contact 27.

The physical counterparts of the pertinent diagrammatically shown elements of Figs. 2 and 3 appear in Figs. 4 to 8, the elements being shown in flash position. Moveable blade 16 is shown affixed to the switch case 11 through rivet member 30. At its upper end it engages stationary contact 17. Blade 18 is also affixed to the switch case through a rivet type member 31 and engages the stationary contact 19 at its upper end. Both these blades are initially positioned to the left, as viewed in Figs. 7 and 8, and are held in this position by the pivoted latch member 22. This latch member is held in the position shown in Figs. 7 and 8 by the bimetallic prop member 21 (Fig. 4) which is affixed at its lower end at 32 and 33. Prop member 21 is of U-shaped construction (Fig. 6) and is caused to receive a flow of current at the end of a timed flash interval, as above described, to cause flexing of said bimetal prop toward the left as shown in Fig. 4 to thereby permit latch member 22 to rotate counter-clockwise and thereby permit blades 16 and 18 to move to engage contacts 26 and 27, respectively. These latter contacts are mounted on a single bus member 34 which is affixed to the switch case through a combination terminal and rivet member 35.

The latch member 22 (Fig. 9), preferably molded of Bakelite, comprises a body portion 36, blade engaging extensions 37, pivot extensions 38, and a prop engaging surface 39. The pivots are journaled in square bearings 41 formed in sidewalls 42 which are integrally molded in the switch case (see Figs. 5 and 7). Bus member 34 has an extension 34a to hold the latch pivots in the square bearings. The latch member is provided with a cam-engaging surface 43 through which it can be manipulated by a cam member 44 which, in turn, is rotated by the manual knob 13. Upon manipulation of the manual knob to the "off" position, latch member 22 is rotated clockwise through surface 43 into position where it can be held by prop 21. It is in this manner that the latch system and the blades 16 and 18 are reset for subsequent flashing operation. When the manual control knob is turned to any of its "on" positions, cam member 44 no longer engages latch member 22. Thereafter, release of the latch member by the bimetallic prop 21 is necessary to cause blades 16 and 18 to move to their normal energization positions.

To provide a damped or retarded motion of switch blades 16 and 18, so that they will move slowly to their normal operation position, latch member 22 has its body portion 36 provided with a hole 45 into which is inserted a resilient absorbent pad 46, such as sponge rubber, impregnated with special damping grease. The width of the body portion 36 of the latch member is nominally $1/8$ " while the inner lands of sidewalls 42 are spaced $3/2$ " apart. The rubber pad before insertion has a thickness of $1/16$ " and is compressed between the lands upon insertion of the pivoted extensions 38 into the journals in sidewalls 42. By this arrangement a damping device is obtained wherein close tolerances are avoided.

Preferably the latch member 22 has waffled end surfaces, as may be seen in Fig. 9. The pores of the latch member retain the grease, and the pockets formed by the waffling of the end surfaces are considered to be a desirable refinement from the standpoint of enhancing the grease retaining action.

Another form of damping latch arrangement is shown in Figs. 11 to 14. In this embodiment, no resilient body is used. Rather, the clearance between the lands of the sidewalls 42 is reduced and a space on each side of the latch is filled with a damping grease given the general designation 56. To help maintain the grease in the clearance space on each side of the latch and to improve the flow of the damping fluid, grooves 54 are formed in the sidewalls 42, as shown in Figs. 11 and 13. Further, a small hole 52 is provided in the body of the latch to permit equalization of the grease flow between the two clearance spaces. The edge portions of the latch 22a and the cooperating portions of the lands of sidewalls 42 are recessed at 54 and 55, respectively. The spaces provided permit improved storage capacity for the damping grease. The recesses of the latch member also provide scraper edges thereon.

An understanding of the effect of the clearances on, for example, the second embodiment, can be had by reference to Fig. 15. In this figure is plotted the length of time for the latch to move from one stationary contact position to the second stationary contact position as a function of the total clearances between lands and the body of the latch 22a. In the test from which this data was derived the driving force inherent in the bias of blades 16 and 18 was in the order of 180 grams. It can be seen from curve A that very little damping is obtained by the use of air as a fluid medium. As shown by B and C, substantial damping is obtained even at clearances in excess of .010" with use of fluids of 30,000 and 60,000 cstks. viscosity, respectively. Although much greater damping can be had by reducing clearances as shown in the vicinity of the .002" to .006" clearances, it is more advisable to use the damping characteristics which are substantially independent of change of clearance distances. For this reason these damping arrangements are substantially unaffected by wear as under severe service conditions. Larger clearances also help prevent gumming of the latch due to dirt accumulation. In the tests from which the curves B and C were derived, the greases used were of the type known commercially as DC (Dow Corning) 200, or equivalent. These greases are fairly heavy, and by their use in combination with either embodiment of the present invention, special glands or packings are unnecessary for grease retention.

The time for travel of a latch is given in Fig. 15 in half cycles of a 60 cycle/sec. alternating current. While it is normally considered that the arc should be extinguished at the first current zero, it was found that a great number of "pop-overs" occurred if the travel time was less than approximately 6 to 8 half cycles.

While the present invention is particularly intended for use in the manner described, it is intended that the invention shall be applicable to any use to which it may be applied by those skilled in the art. Further, while only two forms of the invention have been shown, variations like the substitution of an impregnated felt pad for the sponge rubber pad of Fig. 9 and any other modification within the spirit of the invention

are considered within the scope of this invention.

I claim:

1. In a switching device for controlling an electrical heating load from an electrical supply line, a first stationary contact adapted to be connected to a line conductor at a first potential, a second stationary contact spaced from said first contact by a predetermined distance and adapted to be connected to a line conductor at a second potential, a movable contact arranged for movement between said stationary contacts and adapted to be connected to said heating load to apply said potentials thereto, said movable contact being spring-biased toward said second stationary contact, means including a movable member operatively associated with said movable contact for initially positioning and latching the movable contact in engagement with said first stationary contact, and for releasing said movable contact to permit it to move to said second stationary contact under its spring bias, and means for retarding movement of said movable contact, to thus retard movement of said movable contact, sufficiently to permit dissipation of any arc drawn by said movable contact in moving from said first stationary contact and thereby prevent establishment of a continuous arc between said stationary contacts.

2. In a switching device for controlling an electrical heating load from an electrical supply line, a first stationary contact adapted to be connected to a line conductor at a first potential, a second stationary contact spaced from said first contact by a predetermined distance and adapted to be connected to a line conductor at a second potential, a movable contact arranged for movement between said stationary contacts and adapted to be connected to said heating load to apply said potentials thereto, said movable contact being spring-biased toward said second stationary contact, means including a movable member operatively associated with said movable contact for initially positioning and latching the movable contact in engagement with said first stationary contact, and for releasing said movable contact to permit it to move to said second stationary contact under its spring bias, means forming at least one stationary surface in close proximity to said member, and means including a fluid medium between said member and said surface for retarding movement of said member, to thus retard movement of said movable contact, sufficiently to permit dissipation of any arc drawn by said movable contact in moving from said first stationary contact and thereby prevent establishment of a continuous arc between said stationary contacts.

3. In a switching device for controlling an electrical heating load from an electrical supply line, a first stationary contact adapted to be connected to a line conductor at a first potential, a second stationary contact spaced from said first contact by a predetermined distance and adapted to be connected to a line conductor at a second potential, a movable contact arranged for movement between said stationary contacts and adapted to be connected to said heating load to apply said potentials thereto, said movable contact being spring-biased toward said second stationary contact, means including a movable member operatively associated with said movable contact for initially positioning and latching the movable contact in engagement with said first stationary contact, and for releasing said movable contact to permit it to move to said second stationary

contact under its spring bias, means forming at least one stationary surface in close proximity to said member so as to provide a space between said surface and said member, and means including a fluid medium between said member and said surface for retarding movement of said member, to thus retard movement of said movable contact, sufficiently to permit dissipation of any arc drawn by said movable contact in moving from said first stationary contact and thereby prevent establishment of a continuous arc between said stationary contacts, said space being characterized by the absence of packing or the equivalent to maintain the fluid medium in said space.

4. In a switching device for controlling an electrical heating load from an electrical supply line, a first stationary contact adapted to be connected to a line conductor at a first potential, a second stationary contact spaced from said first contact by a predetermined distance and adapted to be connected to a line conductor at a second potential, a movable contact arranged for movement between said stationary contacts and adapted to be connected to said heating load to apply said potentials thereto, said movable contact being spring-biased toward said second stationary contact, means including a movable member operatively associated with said movable contact for initially positioning and latching the movable contact in engagement with said first stationary contact, and for releasing said movable contact to permit it to move to said second stationary contact under its spring bias, said member having flat opposed faces, means forming stationary flat surfaces in close proximity to the opposed faces of said member, and means including a fluid medium between each of said surfaces and the adjacent face of said member for retarding movement of said member, to thus retard movement of said movable contact, sufficiently to permit dissipation of any arc drawn by said movable contact in moving from said first stationary contact and thereby prevent establishment of a continuous arc between said stationary contacts.

5. In a switching device for controlling an electrical heating load from an electrical supply line, a first stationary contact adapted to be connected to a line conductor at a first potential, a second stationary contact spaced from said first contact by a predetermined distance and adapted to be connected to a line conductor at a second potential, a movable contact arranged for movement between said stationary contacts and adapted to be connected to said heating load to apply said potentials thereto, said movable contact being spring-biased toward said second stationary contact, means including a movable member operatively associated with said movable contact for initially positioning and latching the movable contact in engagement with said first stationary contact, and for releasing said movable contact to permit it to move to said second stationary contact under its spring bias, said member having flat opposed faces and having an aperture extending between said faces, means forming stationary flat surfaces in close proximity to the opposed faces of said member, a resilient absorbent pad carried within said aperture and engaging said surfaces, and a fluid medium impregnating said pad, whereby movement of said member is retarded, to thus retard movement of said movable contact, sufficiently to permit dissipation of any arc drawn by said movable contact in moving from said first stationary contact and thereby prevent establishment of a continuous arc between said stationary contacts.

6. A device according to claim 5, wherein said resilient pad is compressed between said stationary surfaces.

7. In a switching device for controlling an electrical heating load from an electrical supply line, a first stationary contact adapted to be connected to a line conductor at a first potential, a second stationary contact spaced from said first contact by a predetermined distance and adapted to be connected to a line conductor at a second potential, a movable contact arranged for movement between said stationary contacts and adapted to be connected to said heating load to apply said potentials thereto, said movable contact being spring-biased toward said second stationary contact, means including a movable member operatively associated with said movable contact for initially positioning and latching the movable contact in engagement with said first stationary contact, and for releasing said movable contact to permit it to move to said second stationary contact under its spring bias, said member having flat opposed faces and having an aperture extending between said faces, said member also having scraper edges thereon, means forming stationary flat surfaces with grooves therein in close proximity to the opposed faces of said member, and a fluid medium within said aperture and between said surfaces and the faces of said member for retarding movement of said member, to thus retard movement of said movable contact, sufficiently to permit dissipation of any arc drawn by said movable contact in moving from said first stationary contact and thereby prevent establishment of a continuous arc between said stationary contacts.

8. In a switching device for controlling an electrical heating load from an electrical supply line, a first stationary contact adapted to be connected to a line conductor at a first potential, a second stationary contact spaced from said first contact by a predetermined distance and adapted to be connected to a line conductor at a second potential, a movable contact arranged for movement between said stationary contacts and adapted to be connected to said heating load to apply said potentials thereto, a movable member operatively associated with said movable contact for movement conjointly therewith, said member having flat opposed faces and having an aperture extending between said faces, means forming stationary flat surfaces in close proximity to the opposed faces of said member, a resilient absorbent pad carried within said aperture and engaging said surfaces, and a fluid medium impregnating said pad, whereby movement of said member is retarded, to thus retard movement of said movable contact, sufficiently to permit dissipation of any arc drawn by said movable contact in moving from said first stationary contact and thereby prevent establishment of a continuous arc between said stationary contacts.

9. In a switching device for controlling an electrical heating load from an electrical supply line, a first stationary contact adapted to be connected to a line conductor at a first potential, a second stationary contact spaced from said first contact by a predetermined distance and adapted to be connected to a line conductor at a second potential, a movable contact arranged for movement between said stationary contacts and adapted to be connected to said heating load to apply said potentials thereto, a movable member operatively

associated with said movable contact for movement conjointly therewith, said member having flat opposed faces and having an aperture extending between said faces, said member also having scraper edges thereon, means forming stationary flat surfaces with grooves therein in close proximity to the opposed faces of said member, and a fluid medium within said aperture and between said surfaces and the faces of said member for retarding movement of said member, to thus retard movement of said movable contact, sufficiently to permit dissipation of any arc drawn by said movable contact in moving from said first stationary contact and thereby prevent establishment of a continuous arc between said stationary contacts.

10. In a system for flashing an electrical heating unit and for effecting subsequent normal energization of said unit, a supply line providing different potentials, switch means operable between a flash position and a normal position and being biased toward the normal position, connections controlled by said switch means to effect flash and normal operation of said heating unit, means including a movable member operatively associated with said switch means for initially positioning and latching the switch means in the flash position, and for releasing the switch means to permit the latter to move to the normal position, the switch means being subjected to different line potentials conducive to arcing in the process of switch-over from flash to normal operation, and means for retarding movement of said member to thus retard the switch-over action of said switch means, sufficiently to permit dissipation of any arc and

to prevent establishment of a continuous arc through the switch means.

11. In a system for flashing an electrical heating unit and for effecting subsequent normal energization of said unit, a supply line providing different potentials, switch means operable from a flash position to a normal position, connections controlled by said switch means to effect flash and normal operation of said heating unit, the switch means being subjected to different line potentials conducive to arcing in the process of switch-over from flash to normal operation, a movable member operatively associated with said switch means for movement conjointly therewith, said member having flat opposed faces and having an aperture extending between said faces, means forming stationary flat surfaces in close proximity to the opposed faces of said member, a resilient absorbent pad carried within said aperture and engaging said surfaces, and a fluid medium impregnating said pad, whereby movement of said member is retarded, to thus retard the switch-over action of said switch means, sufficiently to permit dissipation of any arc and to prevent establishment of a continuous arc through the switch means.

JOHN J. LAWSER.
